UNITED STATES PATENT OFFICE.

ABRAHAM L. A. HIMMELWRIGHT, OF NEW YORK, N. Y., ASSIGNOR
TO THE NEW JERSEY WIRE CLOTH COMPANY, OF TRENTON, NEW
JERSEY, A CORPORATION OF NEW JERSEY.

FIREPROOF WALL.

SPECIFICATION forming part of Letters Patent No. 792,593, dated June 20, 1905.

Application filed July 16, 1903. Serial No. 165,788.

To all whom it may concern:

Be it known that I, ABRAHAM L. A. HIMMELWRIGHT, a citizen of the United States, residing at New York, county of New York, and State of New York, have invented certain new and useful Improvements in Fireproof Walls, fully described and represented in the following specification and the accompanying drawings, forming a part of the same.

10 The object of the present invention is to provide an improved concrete wall or partition for buildings in which the concrete shall be firmly anchored to the metal members and to produce a structure of great strength for 15 its thickness, while quickly and cheaply built.

A construction embodying the invention in the preferred form will now be described in connection with the accompanying drawings, forming a part of this specification, and the 20 features forming the invention then specifically pointed out in the claims.

In the drawings, Figure 1 is a side elevation, partly broken away, of a wall embodying the invention. Fig. 2 is a horizontal section of the same. Fig. 3 is a vertical section 25 of the same with the concrete partly broken away to show the construction.

In erecting the wall metal studs A are set up at suitable distances apart, these studs preferably being channel-irons, as shown and as usual in such constructions, and after these studs are set up and suitably secured to form a metal framework the concrete B is filled in to form the wall in which the studs A are embedded. As the concrete is filled in from below horizontal metal rods C are inserted at intervals, these rods being passed through holes in the studs A and being spaced at suitable distances apart to give the required anchorage 35 for the concrete against sidewise strain. After the wall is completed the surface may be covered with a facing D, of plaster or similar plastic material, as shown in Fig. 2, or the surface may be left uncovered or finished in 40 any suitable manner on the outside with brick or stone, according to the character of the construction in connection with which the invention is applied. The concrete is preferably

filled in to form the wall by erecting temporary wood centerings on opposite sides of the 50 studs A, filling in the concrete for a short distance from the bottom, putting in the rods C on the concrete filled in, then increasing the height of the centering, filling in more concrete and putting in rods, &c., until the wall 55 is completed.

It will be seen that the construction is very simple and readily built, while at the same time the rods C securely anchor the concrete to the studs A, producing a wall that may be 60 made quite thin, while securing the desired transverse strength. With channel-irons, as shown, the concrete blocks between the channel-irons are anchored at one end by the flanges of the channel-irons, and such anchorage may 65 be sufficient for this end of the concrete blocks unless the studs be widely separated. The channel-irons, however, afford no anchorage for the other ends of the concrete blocks between the channel-irons, and it is found in 70 practice that the concrete is liable to break away from the rear or unflanged side of the channel-irons. My invention provides anchorage for the concrete on this side of the 75 channel-irons and greatly strengthens the construction.

I have shown the length of the rods C as substantially that of the distance between the studs A and arranged so that alternate rods in a stud pass through substantially the width 80 of the body of concrete on opposite sides of the stud, so that an anchorage is secured for practically the whole body of concrete, which enables the desired strength to be secured with the studs spaced well apart. It will be 85 understood, however, that if the studs are placed closer together the rods may extend only a short distance on each side of the studs if channel-irons be used, the more important feature in such case being the anchorage of 90 the ends of the concrete blocks on the rear or unflanged side of the channel-irons.

What I claim is—

1. A wall or similar vertical structure consisting of vertical metal studs, a concrete filling forming a solid wall between the studs, 95

and rods between the studs forming an anchorage for the concrete and passing through the studs, said rods being formed in sections of such length that they may be inserted between adjacent studs and passed through the studs after the studs are in position, substantially as described.

2. A wall or similar vertical structure consisting of vertical channel-irons, a concrete filling forming a solid wall between the channel-irons, and rods between the channel-irons forming an anchorage for the concrete and passing through the channel-irons, said rods being formed in sections of such length that they may be inserted between adjacent studs and passed through the studs after the studs are in position, substantially as described.
3. A wall or similar vertical structure con-

sisting of vertical metal studs, a concrete filling forming a solid wall between the studs, and rods embedded in the concrete filling and not secured to the framework but held in position by engagement with the studs to form an anchorage for the concrete, said rods being formed in sections of such length as to be inserted between adjacent studs and engaged with the studs after the studs are in position, substantially as described.

In testimony whereof I have hereunto set my hand in the presence of two subscribing witnesses.

ABRAHAM L. A. HIMMELWRIGHT.
